UNITED STATES PATENT OFFICE.

JULIA A. FLOOD, OF BOSTON, MASSACHUSETTS.

GAGE FOR SEWING-MACHINES.

No. 876,162.

Specification of Letters Patent.

Patented Jan. 7, 1908.

Application filed April 25, 1907. Serial No. 370,167.

To all whom it may concern:

Be it known that I, JULIA A. FLOOD, a citizen of the United States of America, and resident of Boston, county of Suffolk, Commonwealth of Massachusetts, have invented certain new and useful Improvements in Gages for Sewing-Machines, of which the following is a specification.

My invention relates to a gage for sewing machines which is adapted to be used for both wide and narrow hems.

In dress-making and other like work it is often desirable to make wide hems and the only gage in common use for domestic sewing machines is the one only adapted to narrow work.

My gage is intended to be used for both wide and narrow work and it consists of the structure hereinafter described and claimed.

Figure 1 is a perspective view of the gage showing its application to the plate of the machine and Fig. 2 is a cross section across the flat bar in rear of the guide.

The flat bar A is preferably divided off into inches and fractions thereof and at one end it is attached to the plate of the machine by means of the screw C using the screw hole which is commonly found in domestic machines for securing attachments. The work is guided by a guide B which is adapted to slide on the flat bar so that there will be nothing projecting beneath the under surface of the bar. The slide is composed of a vertical flange b which acts to guide the work with jaws extending back from flange and adapted to clasp the edges of the bar. Each jaw is composed of a horizontal plate b³ which extends at right angles to the horizontal flange b⁴ turned back from the lower edge of the flange b and the flange b³ is turned down over the edge of the bar to form a jaw. Extending up from the flange b³ are the two flanges b⁵ these flanges being separated by a space sufficiently wide to allow the head of the screw c to pass. The flanges b⁵ are united by a clamping screw b⁶ by which the jaws are set against the edges of the bar and a nut b⁷ is provided into which the end of the screw extends.

An opening is formed in the center of the flange b through which passes the head of the screw c and thus it will be seen that the slide will pass entirely over the screw head and may be worked up close to the presser foot d or back at the end of the bar, as desired. The screw b⁶ when loosened releases the jaws and

when tightened holds them firmly on the bar. By means of the slot a the gages may be set so that the inches will come even on any domestic or other machine. The slide as here shown is adapted to be formed of a single piece of sheet metal by suitable dies.

The device is adapted to be used on the various kinds of domestic machines for either wide or narrow work. It can be quickly adjusted and is adapted to be cheaply manufactured.

The edges of the flat bar are rounded as here shown whereby they are adapted to be seized by the jaws of the slide to hold the latter firmly in place but they may be of any other suitable form.

I claim—

1. The herein described gage for sewing machines consisting of a flat bar having an opening at one end for the passage of a fastening screw and a transverse guide adapted to slide on said bar and having jaws which clasp the edge of said bar and substantially flush with the under face of the same and a tightening screw connecting said jaws.

2. The herein described gage for sewing machines consisting of a flat bar having an opening at one end for the passage of a fastening screw and a guide adapted to slide on said bar, said guide having a vertical flange with a central opening to admit the passage of the screw head and jaws adapted to clasp the edges of said bar extending back from said flange with a space between them wide enough for the passage of the screw head and a tightening screw connecting said jaws.

3. The herein described gage for sewing machines consisting of a flat bar having an opening at one end for the passage of a fastening screw and a guide adapted to slide on said bar, said guide having a vertical flange with a central opening to admit the head of the screw and jaws extending back from said flange and adapted to clasp the edges of the bar each jaw having a vertical flange separated by a space sufficiently wide to allow of the passage of the screw head and a screw passing through said flanges for clamping said jaws.

Signed by me at Boston, this 20th day of April A. D., 1907.

JULIA A. FLOOD.
